UNITED STATES PATENT OFFICE.

FREDERICK W. NURENBERG, OF NEW YORK, N. Y., ASSIGNOR TO THE FAIRBANKS COMPANY, OF SAME PLACE.

DESIGN FOR A FRAME FOR COPYING-PRESSES OR LIKE ARTICLES.

SPECIFICATION forming part of Design No. 32,830, dated June 12, 1900.

Application filed May 10, 1900. Serial No. 16,232. Term of patent 14 years.

To all whom it may concern:

Be it known that I, FREDERICK W. NURENBERG, a citizen of the United States, residing at the city of New York, (Brooklyn,) county 5 of Kings, and State of New York, have invented and produced a new and original Design for Frames for Copying-PresSES or Like Articles, of which the following is a specification.

My invention relates to a new and original 10 design for frames for copying-presses and like articles, and the same resides in the configuration and disposition of parts hereinafter described.

Figure 1 is a side elevation of the frame; 15 Fig. 2, a vertical section centrally through the frame, substantially on the line 2 2, Fig. 1, looking in the direction of the arrow. Fig. 3 is a section through the frame horizontal on the plane of the line 3 3.

20 In the drawings, 1 represents the side pieces, 2 a central cross-piece or arch, and 3 arms extending upwardly from the arch within the vertical plane of the side pieces.

At 4 is a rib on the inside of the arms extending upwardly and increasing in depth as 25 it follows the line of the arch 2, where at the center it is swelled outwardly to form the boss 5, having a cylindrical bore 6, said boss being in cross-section conformed to the shape 30 of an inverted cone.

At the top the arms 3 are bifurcated, as at 7, and on the inside they are provided with a groove 8, leading down to the arch, which is flat on top.

I claim as my invention-- 35
The design for a frame for copying-presses, and like articles, substantially as herein shown and described.

Signed at the city, county, and State of New York, this 29th day of April, 1900.

FREDERICK W. NURENBERG.
